Theophilus Hokkanen

UNITED STATES PATENT OFFICE.

THEOPHILUS HOKKANEN, OF NEW YORK, N. Y.

VALISE.

1,413,852.

Specification of Letters Patent. Patented Apr. 25, 1922.

Application filed March 29, 1921. Serial No. 456,598.

To all whom it may concern:

Be it known that I, THEOPHILUS HOKKANEN, a citizen of Republic of Finland, and a resident at the borough of Manhattan, 5 in the city of New York and State of New York, have invented a new and Improved Valise, of which the following is a full, clear, and exact description.

This invention relates to valises of that 10 type commonly known as suitcases, hand bag, etc., and its primary object resides in the provision of receptacles of this character conveyable on wheels so that it will not be necessary to carry them.

15 Another object of the invention is the provision of such receptacles with detachable wheels, so designed as to be reliable, convenient in use, composed of comparatively few parts and occupy a small space.

20 With these and other objects in view the invention comprises various novel features of construction and arrangement of parts which will be more fully described hereafter and set forth in the claims appended 25 hereto.

In the accompanying drawings, which illustrate one embodiment of the invention as applied to a suitcase, and wherein similar reference characters are employed to designate 30 the corresponding parts;

Fig. 1 is a side view of the invention.

Fig. 2 is a front view of the same.

Fig. 3 is an enlarged section along the line 3-3 of Figure 2.

35 Fig. 4 is an enlarged bottom view of the wheels and their support with sectional view through one wheel and part of wheel supporting bracket.

Fig. 5 is an enlarged front view of the 40 wheels and their supporting mechanism.

While I have shown the invention in its embodiment as a suitcase it is to be understood that the shape and construction of the receptacle is independent of this invention 45 and the invention applies equally well to valises and receptacles of any other type.

Referring to drawings numeral 6 designates a receptacle, a suitcase arbitrarily chosen for the case illustrated, provided with 50 a handle 7 of usual construction at one end and metallic channel shaped member 8 securely fastened on opposite end. The U-shaped clip 9 is securely fastened on channel 8 in the manner illustrated on the drawings 55 to form a pocket for the reception of a bearing bracket 10. The locking spring 11 is

also securely mounted on channel 8 at 12 and adapted to hold the bent end of the bearing bracket 10 between the channel 8 and clip 9 as illustrated. Tension in the locking 60 spring 11 is adapted to hold it in the position indicated by full lines on Figure 3. The hole 17 is provided in the channel 8 to enable the locking spring 11 to be pressed to a position permitting insertion of the 65 bracket 10. The bearing bracket 10 carries wheels 13 and 13' on bearing pins 14 and 14' thereby forming a carriage or truck. The wheels 13 and 13' are provided with rubber tires 15 and 15' and are adapted to revolve 70 freely and independently of each other on pins 14 and 14' which are securely fastened in the bearing bracket 10 with pins 16 and 16'.

As pointed out the wheels with their bearing bracket 10 are detachable in a unit from the valise by pressing the locking spring 11 to a retracted position. Similarly the wheel set is attached by pressing said spring and sliding the bracket 10 in its place where it 80 is automatically locked by the spring 11. The wheel set once detached may be packed inside the valise or elsewhere.

The relative location of handle 7 and set of wheels on valise is preferably such that 85 the center of gravity of the receptacle 6 will fall approximately on the line joining the first two.

To convey my improved valise on wheels it is to be held by handle 7 in such a position that its center of gravity is over the wheels thus transmitting nearly all the weight of the valise to the wheels and a very slight force is required to move it along. 95

As pointed out the two wheels used are adapted to turn independently of each other to enable the valise to turn on wheels any way desired.

While I have shown two wheels which I 100 now consider the best combination, any desired number of wheels may be used. The handle 18 is provided for carrying the valise while the wheels have been detached. In the case of hand bags the wheels are most conveniently mounted on the bottom and no extra handle is needed.

From the foregoing description taken in connection with accompanying drawings, the advantages of the invention shown will 110 be readily understood by those skilled in the art to which the invention appertains,

and while I have described the valise which I now consider to be the best embodiment thereof, I desire to have it understood that the combination is only illustrative and such changes as are within the scope of appended claims may be made when desired.

Having thus described my invention I claim as new and desire to secure by Letters Patent is:

- 10 1. The combination with an article of baggage of a carriage therefor, a clip mounted on said article of baggage, said carriage including a bar received in said clip, and a leaf spring for engaging one end 15 of said bar.
2. The combination with an article of baggage of a carriage therefor, a laterally extending member secured to said carriage, means on said article of baggage for receiving said laterally extending member, and a leaf spring adapted to engage an end of said member.
3. The combination with an article of baggage having a pocket formed thereon of 25 a carriage therefor, said carriage including a portion received in said pocket, and a leaf

spring secured to the article of baggage opposite one end of the pocket.

4. The combination with an article of baggage of a carriage therefor, a U-shaped 30 clip mounted on said article of baggage, said carriage including an angular member received in said U-shaped clip, and a leaf spring for engaging said angular member.

5. An article of baggage having a pocket 35 adapted to receive a portion of a carriage, and means mounted on the article of baggage opposite the pocket and spaced therefrom for locking the carriage in place.

6. An article of baggage having a pocket 40 adapted to receive a portion of a carriage, and a leaf spring mounted on said article of baggage opposite the pocket and spaced therefrom.

In testimony whereof I have signed my 45 name to this specification in presence of two subscribing witnesses.

THEOPHILUS HOKKANEN.
